BOTTLE BAG

Sophie J. Thurmer, Brooklyn, N. Y.

Application December 4, 1933, Serial No. 700,901

4 Claims. (Cl. 229—56)

This invention relates to devices for carrying bottles and the like and particularly an improved bottle carrying bag or a bottle bag adapted to carry a number of bottles and hold them in desired positions, the object being to provide an improved construction whereby bottles may be maintained separate and in a desired upright position during the carrying operation and also when the bag is set down.

Another object of the present invention is to provide a bottle bag or carrier for bottles which may be made from paper, cloth or other suitable material and provided with one or any desired number of partitions designed to separate and protect the respective bottles from each other.

A still further object of the invention is to provide a bottle-carrying bag presenting a container, the same being formed of any size and shape and provided with square or other shaped dividing members held in place by paste, glue or in other ways.

An additional object is to provide a bottle-carrying bag with one or more division plates, the division plates being either permanently mounted on the bag or removably mounted thereon, but when in use acting to protect and separate the various bottles being carried.

With the foregoing and other objects in view the invention consists of the arrangement and combination of parts herein described and claimed. While the invention is not restricted to the exact details of construction disclosed here-with, still for the purpose of illustration a practical embodiment thereof is had by the accompanying drawing in which like characters designate like parts, and in which—

Figure 1 is a longitudinal vertical section through a desired embodiment of the invention;

Figure 2 is a horizontal sectional view through Figure 1 on the line 2—2;

Figure 3 is a vertical sectional view through Figure 1 approximately on the line 3—3;

Figure 4 is a view similar to Figure 1 but showing a modified arrangement of the partition members wherein the bottom is divided by the partition members;

Figure 5 is a view similar to Figure 2 but showing a single pair of partitions connected by the bottom member;

Figure 6 is a sectional view similar to Figure 2 but showing a modified form of partition;

Figure 7 is a perspective view of the partition shown in Figure 6, the same being on an enlarged scale;

Figure 8 is a view similar to Figure 6 but showing a slightly modified form;

Figure 9 is a view similar to Figure 6 but showing a further modified form;

Figure 10 is a view similar to Figure 9 but showing a modified construction thereof.

Referring to the accompanying drawing by numerals, 1 indicates a bag which may be formed of paper, fiber, cloth or other desired material. This bag is preferably turned over at 2 to provide a thickened portion at the top to which the respective handles 3 and 4 are secured by suitable staples 5. To carry bottles or similar articles in an ordinary bag of this type would be rather difficult if it was desired to carry the bottles standing upright. In order to secure this result, namely, the carrying of bottles in an upright position, a tubular member 6 is secured to the bag 1 in any desired manner, preferably by adhesive strips 7 and 8.

The tubular member 6 is shown as square in Figure 2, but it will be evident that it may be round or any other desired shape. This member may be made of any desired grade of paper, cardboard or corrugated paper. It may also be of any desired height, preferably of a height extending upwardly beyond the thickened part of the bottle, though this is not absolutely essential. When this structure is used three bottles may be carried as shown in dotted lines in Figures 1 and 2, or, if desired, one or two bottles. The various bottles will be maintained separate and also held normally in an upright position either by the bag or by the division or partition member 6.

In Figure 4 a slightly modified structure to that shown in Figure 1 is illustrated. In this form of the invention the structure is identical to that shown in Figure 1 except that the member 6' is provided with a bottom 9 which may or may not be secured to the bottom of the bag.

Instead of having a complete tube or squared member 6 a member 10 might be used as shown in Figure 5, said member having upright sides 11 and 12 and a connecting bottom 13 which bottom is secured in place by the strip 14 of adhesive.

Under many circumstances it may be desired to carry more than three bottles in the bag, and when this is the case the structure shown in Figures 6 and 7 may be used. In this form of the invention the bag 1 as shown in Figure 1 may be used, but the division member 15 is quite different, though it divides the bag into square compartments. In this form there is provided a strip of paper, pasteboard, cardboard or the like 16, secured by adhesive at the flanges 17 and 18, this

division member having notches at 19 and 20 so that the rectangular division member 21 may be fitted therein, said rectangular member also being notched as shown in Figure 7 whereby the 5 parts form a division unit dividing the interior of the bag into blocks, there being six blocks or chambers illustrated. As shown in Figure 8, the same general idea is present, but instead of having a rectangular member as shown in Figure 6, 10 merely sheets or plates 22 and 23 are used.

In Figure 9 a further modified idea is presented, embodying the same general idea of dividing a bag into chambers. In this form of the invention a single member 24 divides the bag into two compartments, said member 24 having flanges 25 and 26 secured by adhesive or other means to the 15 sides of the bag.

In Figure 10 the division member 24' is provided with extra long flanges 27 and 28, said 20 flanges extending from the division member to the respective sides of the bag, whereby the division member is held in place by friction and without the use of adhesive or similar securing means.

If desired, the adhesive could be left off the 25 flanges 17 and 18. When this is the case the division structure 15, as illustrated in Figure 7, may be bodily applied and bodily removed. In all forms of the invention some form of division or separating structure is presented which will hold 30 one or more bottles vertically in the bag, and in addition will separate the bottles with a division member which will act as a cushion so that the bottles will not strike together.

I claim:

35 1. A bottle bag comprising a bag structure hav-

ing a reinforced top and a pair of handles connected to said top, a rectangular partition member arranged in the bag and extending from the bottom upwardly a predetermined distance and dividing the bag into a plurality of compartments, 80 two walls of said partition member being connected for their full height to said bag, said partition member and each compartment being adapted to receive a bottle to be held upright by the bag assisted by the partition member. 85

2. A bottle bag comprising a bag structure for carrying bottles in a substantially vertical position, and a partition member formed with four equally formed side panels and a bottom, said bottom being connected to the bottom of said 90 bag and two of said side panels being connected to the sides of the bag and extending from the bottom upwardly, said partition being adapted to receive a bottle and to form with the bag two chambers for receiving bottles. 95

3. A bottle bag comprising a bag structure and a partition member arranged within the bag structure, said partition member having enclosing walls and a bottom, and means for connecting said partition member firmly to the bag. 100

4. A bottle bag for carrying bottles in an upright position, comprising a body, and means for dividing the interior of the body into compartments, said means having a pair of side members extending from one side to the other side of the 105 body, and a bottom member connected to the bottom of the bag.
